CARRYING BAG FOR HAND TOOLS

Ulrich Knigge, Stresemannstrasse 39,
Bremen, Germany

Continuation-in-part of design application Ser. No. 5,332, Jan. 6, 1967. This application Mar. 26, 1968, Ser. No. 11,224

Claims priority, application Germany July 7, 1966

Term of patent 14 years

Int. Cl. D2—01

U.S. Cl. D2—229

Fig. 1

Fig. 2

Fig. 3

FIG. 1 is a front perspective view of a carrying bag for hand tools showing my new design;

FIG. 2 is a side elevation thereof; and

FIG. 3 is a rear elevation thereof.

Portions of a conventional carrying strap have been omitted from the figures for convenience of illustration.

This is a continuation-in-part of design application Ser. No. 5,332, filed Jan. 6, 1967, and now abandoned.

I claim:

The ornamental design for a carrying bag for hand tools, as shown and described.
